PORTABLE SOAP DISH

James Selby Mardre, Jr., Miami, Fla.

Application August 11, 1954, Serial No. 449,143

1 Claim. (Cl. 45—28)

This invention relates to a portable soap dish adapted to provide a cover for a cake of soap to facilitate carrying soap in traveling and being particularly adapted for use by men in the armed forces where it is necessary to store soap in lockers, and in particular a soap dish, preferably formed of plastic wherein a cover is pivotally mounted on a base and the base is adapted to be retained in position on a wall or the like with vacuum cups and wherein the cover is adapted to swing over the vacuum cups to a downwardly disposed position in which the cover provides a brace for supporting the base of the soap dish.

The purpose of this invention is to provide a soap dish of comparatively light weight whereby the soap dish with a cake of soap therein is adapted to be carried in a pocket or handbag or retained in a locker and wherein the soap dish is adapted to be readily set up or attached to a wall, such as the wall of a shower in a bathroom or the like for retaining soap in a convenient position for use.

It is generally considered difficult to provide a soap dish for a shower and particularly where the soap dish is adapted to be used for both a tub bath and a shower and it has also been found difficult to provide means for wrapping a wet cake of soap so that it may be packed and carried from one location to another. With these thoughts in mind, this invention contemplates a soap dish having a body in which a cake of soap may be positioned with vacuum cups positioned on one side of the body for supporting the body from a wall or the like and wherein the body is provided with a hinged cover that is adapted to swing over the vacuum cups and extend downwardly to provide a bracket or support when the soap dish is set up for use.

The object of this invention is, therefore, to provide a portable soap dish that provides a cover for a cake of soap and that may readily be set up and attached to a wall surface when it is desired to use soap therefrom.

Another object of the invention is to provide a portable soap dish having a hinged cover in which the cover is adapted to provide a supporting brace for the soap dish.

A further object of the invention is to provide a portable soap dish having a hinged cover and also having means for temporarily supporting the soap dish on a wall or the like in which the soap dish is of a simple and economical construction.

With these and other objects and advantages in view, the invention embodies a soap dish having a base with end walls and having an arcuate front wall and wherein the rear wall connects the ends of the end walls, a cover having an opening in the rear portion thereof and having flanges at the ends overlapping the end walls of the base pivotally connected through said flanges to the end walls of the base, and vacuum cups mounted by studs on the rear wall of the base.

Other features and advantages of the invention will appear from the following description taken in connection with the drawing, wherein:

2

Figure 1 is a perspective view illustrating the improved soap dish showing the dish with the cover in closed position.

Figure 2 is an elevational view of the improved soap dish showing the cover in the open position in which the cover supports the base and showing the cover in the closed position in dotted lines.

Figure 3 is a cross section through the soap dish taken on line 3—3 of Figure 1, also showing the parts with the cover in the closed position.

Figure 4 is a longitudinal section through the rear portion of the soap dish taken on line 4—4 of Figure 3 illustrating the pivotal connections of the cover to the base, showing the vacuum cups and indicating, by broken lines, the position of the cover with the cover extended downwardly to provide a support for the base.

Referring now to the drawing wherein like reference characters denote corresponding parts, the improved portable soap dish of this invention includes a base 10 having an upwardly sloping and arcuate forward section 11, end walls 12 and 13 and a rear wall 14, a cover 15 having flanges 16 and 17 at the ends with the flanges provided with extensions 18 and 19, respectively, through which studs 20 and 21 extended from the side walls 12 and 13 of the base extend, and, as illustrated in Figures 1 and 3, the upper wall of the cover 15 terminates on a line 22, the line, which forms the edge of the cover, being positioned to engage the lower surface of the base 10 upon swinging the cover over the rear portion of the soap dish to the position shown in Figure 2; and, particularly as shown in Figures 1 and 2, the soap dish is adapted to be temporarily supported with vacuum cups 23 and 24 that are mounted on studs 25 and 26, respectively, in the rear wall 14 of the base.

With the base formed, particularly as illustrated in Figure 3, a cake of soap positioned between the cover and base is protected and may be positioned in a handbag, locker or the like without the wet soap coming in contact with other articles in the handbag or locker. With the cover turned over to the position shown in Figure 2 the soap is exposed and should the soap adhere to the base 10 it may be forced forwardly whereby the arcuate inner surface of the base will cause the soap to slide free of the base.

The cover 15 is provided with an arcuate lip 27 that overlaps the upper edge of the base and the studs 20 and 21 are provided with heads 28 and 29 that prevent the flanges of the cover spreading, thereby providing means for retaining the parts in assembled relation.

The studs 25 and 26 that extend from the rear wall 14 of the base are also provided with heads or flanges, as indicated by the numerals 30 and 31, and these heads or flanges are positioned to be received in annular recesses in the vacuum cups 23 and 24, respectively, whereby the cups are permanently secured to the rear wall 14 of the base.

In use the device is positioned as shown in Figure 2, and a cake of soap is placed in the base, and after use the vacuum cups are removed from the surface of the wall 32 and the cover moved upwardly to its position on the base, as illustrated in Figure 1. With the cover in this position the soap may be placed in a handbag or stored in a locker or the like until use thereof is again desired.

It will be understood that modifications, within the scope of the appended claim, may be made in the design and arrangement of the parts without departing from the spirit of the invention.

What is claimed is:

A portable soap dish comprising a base having an upwardly sloping and arcuate forward section, upwardly extending side walls, an upwardly extending rear wall, a

pair of rearwardly facing suction cups secured to the outer surface of the said rear wall, a cover member which extends from the forward edge of the base rearwardly to a line spaced from and parallel to said rear wall, said cover member having depending side walls which overlap the side walls of the base and which extend the full length of the side walls of the base, and means pivoting the side walls of the cover member to the side walls of the base along an axis parallel to and between said rear wall and said line, the spacing of the cover member from the rear wall being substantially equal to the distance of the outermost part of the suction cups from said rear wall, so that the cover member may be pivoted upwardly and around the suction cups to a position wherein said cover member extends downwardly from the base, with the forward edge thereof in substantially the same plane

as the said outermost part of said suction cups and with the rear edge thereof bearing against the lower surface of the base member whereby said cover serves as a brace when the soap dish is mounted on a vertical supporting surface by means of said suction cups.
